CONTROL MECHANISM FOR VERTICAL
HYDRAULIC BROACHING MACHINES

Kenneth C. Monroe, Hudson, Mass., assignor to
The Lapointe Machine Tool Company, Hudson,
Mass., a corporation of Maine

Application July 12, 1938, Serial No. 218,870

17 Claims.

(Cl. 90—33)

This invention relates to a vertical hydraulic broaching machine and more particularly to broaching machines of the pull-down type in which power-operated devices are provided for restoring the broach to raised position. Such a machine is shown for instance in the prior patent to Donald H. West, No. 2,135,157, dated November 1, 1938.

It is the general object of this present application to provide electrical and hydraulic control devices so interlocked that successive steps in the operation of the machine must be performed in predetermined sequence.

In particular, I provide means insuring that the finished work piece must be removed before the broach is raised, and insuring that the puller head must be fully raised before the broach is lowered by reversal of the broach lifter.

I also provide devices which insure insertion and subsequent removal of the broach-holding key at definite points in the operation of the machine, and which prevent further operation of the machine until such insertion or removal has taken place.

My invention further relates to arrangements and combinations of parts which will be hereinafter described and more particularly pointed out in the appended claims.

A preferred form of the invention is shown in the drawings, in which—

Fig. 1 is a diagrammatic representation of a vertical hydraulic broaching machine of the pull-down type, together with its hydraulic actuating mechanism and with certain hydraulic and electric interlocking devices;

Figs. 2 to 6 inclusive are similar diagrammatic views showing successive positions of different parts of the machine and control devices during a broaching operation; and

Fig. 7 is a sectional side elevation of a broaching machine of the type to which my invention is particularly applicable.

Referring to Figs. 1 and 7, I have shown parts of a vertical pull-down broaching machine comprising a puller head 10 mounted on a slide or ram 11 and connected by a piston rod 12 to a piston 14 slidable in a main cylinder 15. A pump P is connected by a pipe 16 to the upper end of the cylinder 15 and is connected by a pipe 17 to the lower end of said cylinder.

A back pressure valve 18 is inserted in the pipe 17, and a branch connection 19 is provided, through which extra oil may be supplied to the pump during the working or downward stroke. During the up stroke, the pipe 19 is closed by a check valve 20.

The pump P is preferably a variable-discharge, reversible pump and may be of the type shown in the prior patent to West, No. 1,722,832. The

pump P is controlled by a rack bar 21 and pinion 22, as in said prior patent, and the rack bar 21 is shown as connected by a link 23 to a rock arm 24 mounted on a fixed pivot 25.

A knock-off rod 26 has a pin and slot connection with the rock arm 24 and is provided with adjustable collars 27 and 28 positioned for engagement by an arm 30 mounted on a rod 31 which in turn is supported on an upper part of the ram or slide 11. When either collar 27 or 28 is engaged by the arm 30, the rock arm 24 is returned to mid-position and the pump P is adjusted for no-discharge.

A hand lever 33 is pivoted at 34 and has an arm 35 connected by a link 36 to the rock arm 24. A second arm 37 is connected by a link 38 and piston rod 39 to a piston 40 in a relay cylinder 41, said relay being provided for power operation of the pump-adjusting mechanism.

The cylinder 41 is connected by pipes 42 and 43 to spaced ports in the valve casing 44 of a solenoid-operated valve V.

A continuous-discharge auxiliary pump P' is connected through a relief valve 45 and pipe 46 to a supply port in the valve casing 44, and connections 47 and 48 are provided from said casing to storage at atmospheric pressure.

A piston 50 comprising two spaced piston elements is slidable in the casing 44 and is provided with a valve rod 51 connected to a bell crank 52 pivoted at 53 and having a portion 54 extending between electro-magnetic or solenoid coils 55 and 56 and adapted to be attracted thereby. Opposed springs 51a on the piston rod 51 normally center the piston 50 in neutral position, unless displaced therefrom by one or the other of the coils 55 or 56.

Connection is made from a line wire L to each of the coils 55 and 56, and connection is made from the coil 55 through a photoelectric relay 57 to a normally-open switch 58. The coil 56 is similarly connected to a wire 59 through a normally-open switch 60. The other terminals of the switches 58 and 60 are connected by a return wire 61 to a second line wire L'.

If the switch 60 is closed, the coil 56 will be energized, shifting the piston 50 in the valve V to the left and applying pressure through the pipe 43 to the lower end of the relay cylinder 41. This raises the piston 40 and also raises the rack bar 21 and knock-off rod 26. Such movement of the rack bar will cause fluid under pressure to be supplied through the pipe 16 to the upper end of the cylinder 15, thus moving the piston 14 and ram 11 downward for a working stroke.

Similarly, if the switch 58 is closed, the piston 50 in the valve V will be shifted to the right, causing the relay cylinder to shift the pump P to discharge in the opposite direction through

the pipe 17 and thus return the piston 14 and ram 11 to upper position.

The devices for hydraulically operating the rack bar 21, except for the electrical control, are similar to the corresponding devices shown and described in my prior application, Serial No. 169,581 to which reference is made for a more detailed description.

The pipe 16 is also connected through a normally-closed valve 63 to a vent pipe 64. The valve 63 has a pressure connection 65 to the pipe 17, and the construction is such that pressure in the connection 65 will open the valve 63 and vent the pipe 16 to storage. This permits the escape of surplus oil from the upper end of the cylinder during an up stroke, corresponding to the increasing amount of oil displaced by the piston rod as the piston 14 moves upward.

During the broaching stroke, the lower end of the broach B is secured in the puller head 10 by a key 70 and I will now describe certain devices which I have provided for inserting and removing the key and for interlocking the movements of the key with the operation of the broaching machine.

The key 70 is connected by a link 71 to an upwardly extending arm of a four-armed lever 72, pivoted at 73 on a depending support 74 carried by the ram 11. A second arm 75 of the lever 72 has a toggle connection to a spring plunger 76 mounted on a pivot 77. This spring toggle connection causes the lever 72 to be held in one or the other of its extreme positions, as determined by stop pins 78, the construction being similar to that shown and described in the prior application of John W. Forbes, Serial No. 189,744, filed February 10, 1938.

A third arm 80 on the lever 72 engages a fixed stop 81 as the ram 11 approaches its lower limit of travel and the lever 72 is reversed thereby, thus withdrawing the key 70 from holding position.

The fourth arm 82 of the lever 72 is provided with a ball-shaped head positioned between spaced lugs 83 and 84 on a hand lever 85, pivoted at 86 on the support 74 and normally held in mid-position by a spring 87. The upper portion of the handle 85 extends between the normally-open switches 58 and 60 associated with the coils 55 and 56 and is adapted to close one or the other of these switches when displaced to the right or to the left.

When moved to the left, the lever 85 will reverse the four-armed lever 72, moving the lever to the position shown in Fig. 3 and inserting the key 70 in broach-holding position. Also, when thus moved to the left, the lever 85 engages and closes the switch 60, thus energizing the coil 56 and causing the pump P to be shifted to effect a broaching or down-stroke of the ram, all as previously described.

The key-shifting lever 72 is automatically returned to the position shown in Fig. 1 by engagement of the arm 80 with the stop 81 at the lower end of the broaching stroke. Such return movement does not, however, displace the lever 85 from its normal mid position, by reason of the spaced relation of the lugs 83 and 84. The lever 85 may be thereafter moved manually to the right to close the switch 58 and set the pump P for a return stroke of the ram 11. Such movement of the lever 85 to the right will manually reverse the lever 72 and withdraw the key 70, if for any reason these parts have not been moved automatically by engagement of the arm 80 and stop 81.

The broach lifter mechanism is of the general type disclosed in said prior application Serial No. 125,871 and comprises a lifter head 90 mounted on a piston rod 91 and actuated by a piston 92 in a lifter cylinder 93.

A second auxiliary pump P² is connected through a pilot-operated relief valve 94 and through an adjustable needle valve 95 to a supply port in the casing 96 of a solenoid-operated valve V', which casing is provided with three additional ports, one of which is connected through a pipe 97 to the upper end of the cylinder 93. Another port is connected through a pipe 98, back pressure valve 99 and check valve 100 to the lower end of the cylinder 93. A by-pass 101 is provided around the check valve 100, which by-pass contains an adjustable needle valve 102. A fourth port in the casing 96 is connected to an exhaust pipe 103 through which oil may be returned to storage.

One terminal of a solenoid coil 105 at the left-hand end of the valve V' is connected through a wire 110, normally-open hand switch 111, wire 112, limit switch 113 and wires 114 and 61 to the line wire L'. The other terminal of the solenoid coil 105 is connected through a return wire 115 to the line wire L.

One terminal of the solenoid coil 120 at the right-hand end of the valve V' is also connected through the return wire 115 to the line wire L, while the other terminal is connected through a wire 121 to a normally-open switch 122, which in turn is connected through a wire 123 to the line wire L'.

The lifter head 90 is provided with a broach-holding device 125 from which a broach is automatically released by cam action at a predetermined point in its downward travel, all as fully explained in the cited West application.

A latch 126 is pivotally mounted on the lifter head 90 and passes freely by the switch 122 when moved downward but closes the switch on engagement thereof when moving upward.

Upper and lower control valves 130 and 131 are provided in connection with the lifter mechanism, which valves are normally closed but are provided with actuating members 132 and 133 respectively, which members are positioned for alternate engagement by a cam plate 134 on the lifter head 90, according as the lifter head is in raised or lowered position.

A pipe 136 connects the supply pipe 97 for the upper end of the cylinder 93 to a port in the lower side of the upper control valve 130, and a pipe 137 connects the supply pipe 98 for the lower end of the cylinder 93 to a similar port in the lower side of the valve 131.

Upper ports in the valves 130 and 131 are connected to a control pipe 140, which pipe is in turn connected to the pilot-operated relief valve 94. The valve 94 is of a commercial construction such that lack of pressure in the pipe 140 will connect the pump P² direct to the exhaust pipe 141, so that the oil discharged from the pump is returned direct to storage. When there is pressure in the pipe 140, however, the relief valve 94 is closed and the pump P² is connected to the supply pipe 142 of the valve V'. A small by-pass opening in the valve 94 will build up pressure in the pipe 140 and close the relief valve 94 unless one of the valves 130 and 131 is open to atmosphere.

The general operation of my improved broaching machine is as follows: The machine is stopped with the broach B suspended from the raised

lifter head 90 as indicated at A in Fig. 7, and with the ram 11 also in raised position.

After the work has been placed on the fixed work support 150^a (Fig. 7), the lifter head moves the broach downward to position C, thus inserting the lower end of the broach B in the puller head 10 of the ram 11.

The work in this position intercepts the light ray which controls the photoelectric relay 57 and thus opens the operating circuit of the solenoid coil 55.

The ram is then started downward and the broach is pulled through the work by the ram, while at the same time the lifter head exerts downward pressure on the upper end of the broach. As the broaching operation nears completion and the broach is moved down to position D, the lifter head 125 is unlatched to free the broach and the lifter head comes to rest. The ram 11 continues its downward motion and pulls the broach entirely through the work to position E, whereupon the ram and broach come to rest and the key 70 is automatically withdrawn.

The work is then removed, and the ram is started upward, thereby again inserting the upper end of the broach in the lifter head 125 and mechanically moving the lifter head upward far enough to release the broach holder 125 for re-engagement with the broach.

The lifter head then moves rapidly upward, drawing the broach out of the broach holder 10 and returning it to the position A. The machine then comes to rest, with the broach lifter, broach and ram all in raised position. This general operation is substantially as described in the prior West application Serial No. 125,871.

I will now describe in detail the operation of the hydraulic and electric control devices by which successive steps in the operation above outlined are caused to take place in predetermined order and not otherwise.

Assuming that the parts are in the position indicated in Fig. 1, with the broach in the position A of Fig. 7, it will be noted that the limit switch 113 is closed by engagement with the ram 11 in its raised position. The pump control valve V is in its normal mid-position, the main pump P is in neutral, and the lifter control valve V' is in its right-hand position, with the pump P² connected to the lower end of the cylinder 93 but discharging to storage through the exhaust connection 141 by reason of the fact that the control pipe 140 is vented through the open control valve 130.

The operator now closes the switch 111, which shifts the valve V' to the left-hand position shown in Fig. 2. The pump P² is thereby connected through the pipe 97 to the upper end of the lifter cylinder 93 and is also connected through the pipe 136 and open valve 130 to the control pipe 140, so that pressure is immediately built up in the pipe 140 to close the pilot-operated relief valve 94.

The lower end of the cylinder 93 is connected to the exhaust through the needle valve 102 and back pressure valve 99, and the lifter head 90 moves the lower end of the broach B downward through the work and inserts said lower end in the puller head 10 on the ram 11. The pump P² continues to exert pressure above the piston 92 in the cylinder 93, but as no further movement of the piston can take place, the pump P² discharges to atmosphere through the valve 94, 75

which at this time acts merely as an ordinary relief valve.

The operator then shifts the hand lever 85 to the left as shown in Fig. 3, thereby inserting the key 70 in the lower end of the broach B and closing the switch 60 which operates through the valve V and relay cylinder 41 to set the pump P for a down stroke, all as previously described.

As soon as the handle 85 is released, the handle 10 returns to mid position, allowing the switch 60 to open and the valve V to return to mid position. This vents both ends of the cylinder 41 and leaves the pump P free for mechanical shifting to no-discharge position at the end of the broaching stroke.

If the operator inadvertently operates the lever 85 before closing the switch 111, the cam 11 will merely be moved downward idly without the broach and the lifter head will remain in raised position, as the circuit through the switch 111 cannot be completed after the ram 11 has moved away from the limit switch 113, which will then open.

The ram and broach lifter continue to move downward together, both under pressure, until the broach holder 125 engages a fixed cam 150 (Fig. 4) which releases the broach. At the same time the cam 134 on the broach lifter 90 engages and opens the control valve 131, thus venting the control pipe 140 which in turn causes the valve 94 to connect the pump P² to exhaust. The back pressure valve 99 prevents idle downward movement of the lifter head.

As the ram 11 and broach B reach their lower limit of travel, the arm 80 (Fig. 5) of the lever 72 engages the stop 81 and the lever 72 is reversed thereby, thus withdrawing the key 70 but leaving the hand lever 85 in mid position. At the same time, the knock-off arm 39 engages the lower collar 28 on the rod 26 and moves the pump P to neutral or no-discharge position.

The operator then removes the work, after which he moves the hand lever 85 to the right, as also shown in Fig. 5, to close the switch 58. 45 If he closes the switch before removing the work, however, no action will follow, as the photoelectric relay 57 will remain open as long as its controlling light ray is intercepted by the work. Assuming that the work has been removed, closing of the switch 58 will energize the coil 55, moving the piston 56 in the valve V to a position shown in Fig. 5 and moving the pump P to its reverse position in which it delivers oil under pressure to the pipe 17 and raises the ram 11.

55 As the broach B is thus moved upward, it is re-inserted in the broach holder 125 (Fig. 6) of the lifter head 90 and pushes the lifter head upward far enough to permit the broach holder to clear the cam 150 and thereupon grip the broach. Such upward mechanical movement of the broach lifter can take place freely, as the oil ejected from the upper end of the cylinder will escape through the relief valve 94, which is open by reason of the fact that the control pipe 140 is still vented through the control valve 131 as shown in Fig. 4.

As soon as the lifter head 90 has moved a short distance upward, however, the cam 134 releases the valve 131 and the latch 126 closes the switch 122. This completes the circuit through the solenoid coil 120 in the valve V, shifting the valve to the position shown in Fig. 6 and connecting the pump P² to the lower end of the lifter cylinder 93. Both control valves 130 and 131 being now closed, pressure will be

built up in the pipe 140 through the by-pass in the valve 94, the valve 94 will be closed to exhaust, and the pump P² will be operative through the valve V' to raise the lifter head 90.

The pump P² is of such capacity that the lifter head moves upward more rapidly than the ram 11, thus returning the broach B to the position A in Fig. 7 by the time the puller head 10 has reached its raised position. When the lifter head 90 is fully raised, the cam 134 opens the control valve 130, thus venting the pipe 140 and connecting the pump P² to exhaust. At the same time, the knock-off arm 30 engages the upper collar 27 on the rod 26 and returns the main pump P to no-discharge position, thus completing the broaching cycle.

Having described the operation of a machine embodying my invention, it will be clear that the machine is fully safeguarded and that the operator cannot cause damage by improper sequence of operation.

As previously explained in detail, the lifter head cannot be started downward to insert the broach in the work unless the ram 11 is in fully raised position to receive the broach. The ram 11 cannot be started downward for a broaching stroke unless the key 70 has been inserted in the lower end of the broach. The pump P is returned to no-discharge position automatically at the lower end of the stroke, and the key 70 is simultaneously withdrawn automatically. The lever 85 cannot be shifted to close the switch 58 without withdrawal of the key 70, and closing of the switch 58 will not cause the pump P to be rendered operative to lift the ram unless the finished work has been removed from the path of the light ray which controls the photoelectric relay 57.

The control valves 130 and 131 vent the pipe 140 and connect the pump P² to exhaust as soon as the puller head 90 reaches either end of its path of travel, and the switch 122 is closed to reverse the valve V' only on upward movement of the lifter head by pressure of the ram 11 on the broach B after insertion of the upper end of the broach in the holder 125.

The machine is operated by simply closing the switches 111, 60 and 58 in predetermined order, and the operator has nothing else to do except to insert and remove the work.

The photoelectric control of work removal is not limited in utility to broaching machines but is capable of more general application.

Having thus described my invention and the advantages thereof, I do not wish to be limited to the details herein disclosed, otherwise than as set forth in the claims, but what I claim is:

1. In a vertical hydraulic pull-down broaching machine comprising a puller head, a lifter head, a reversible-discharge pump for said puller head and hydraulic shifting mechanism for said pump, that improvement which consists in providing auxiliary hydraulic operating means for said lifter head, and control devices for said auxiliary means which vent said auxiliary means after said lifter head has completed its down stroke and thereby permit said lifter head to be moved upward a limited distance by said puller head without substantial hydraulic resistance to such movement.

2. In a vertical hydraulic pull-down broaching machine comprising a puller head, a lifter head, a reversible-discharge pump for said puller head and hydraulic shifting mechanism for said pump, that improvement which consists in providing

auxiliary hydraulic operating means for said lifter head, and control devices for said auxiliary means which vent said auxiliary means after said lifter head has completed its down stroke and thereby permit said lifter head to be moved upward a limited distance by said puller head without substantial hydraulic resistance to such movement, and which thereafter render said auxiliary means operative to complete the upward movement of the lifter head.

3. In a vertical hydraulic pull-down broaching machine comprising a puller head, a lifter head, a reversible-discharge pump for said puller head and hydraulic shifting mechanism for said pump, that improvement which consists in providing auxiliary hydraulic operating means for said lifter head, and control devices for said auxiliary means which vent said auxiliary means after said lifter head has completed its down stroke and thereby permit said lifter head to be moved upward a limited distance by said puller head without substantial hydraulic resistance to such movement, and which thereafter render said auxiliary means operative to complete the upward movement of the lifter head at increased speed, thereby separating said broach from said puller head.

4. In a vertical hydraulic pull-down broaching machine comprising a puller head, a lifter head and a reversible-discharge main pump for said puller head, that improvement which consists in providing a continuously operating auxiliary pump for said lifter head, vent valves engageable by said lifter head as it approaches its upper and lower limits of travel, and a relief valve controlled thereby and effective to by-pass the output of said auxiliary pump at reduced pressure when said lifter head completes its travel in either direction and one of said vent valves is opened.

5. In a vertical hydraulic pull-down broaching machine comprising a puller head, a reversible-discharge pump for said puller head and hydraulic shifting mechanism for said pump, that improvement which consists in providing a pair of electric switches controlling said shifting mechanism, a broach key inserting device for said puller head, and a manual member operable when shifted in one direction to move said device to insert said key and to simultaneously close one of said control switches to cause said shifting mechanism to be operated.

6. In a vertical hydraulic pull-down broaching machine comprising a puller head, a reversible-discharge pump for said puller head and hydraulic shifting mechanism for said pump, that improvement which consists in providing a pair of electric switches controlling said shifting mechanism, a broach key inserting device for said puller head, a manual member operable when shifted in one direction to move said device to insert said key and to simultaneously close one of said control switches to cause said shifting mechanism to be operated, and means to automatically withdraw said key at the completion of the broaching stroke, said manual member being thereafter operable when shifted in the opposite direction to close the second control switch.

7. In a vertical hydraulic pull-down broaching machine comprising a puller head, a reversible-discharge pump for said puller head and hydraulic shifting mechanism for said pump, that improvement which consists in providing a pair of electric switches controlling said shifting

mechanism, a broach key inserting device for said puller head, and a manual member operable when shifted in one direction to move said device to insert said key and to simultaneously close one of said control switches to cause said shifting mechanism to be operated, and operable when shifted in the opposite direction to close the second switch and to simultaneously withdraw said key if the key is still in broach holding position.

8. In a vertical hydraulic pull-down broaching machine comprising a pulled head, a reversible-discharge pump for said puller head and hydraulic shifting mechanism for said pump, that improvement which consists in providing a pair of electric switches controlling said shifting mechanism, a broach key inserting device for said puller head, a manual member operable when shifted in one direction to move said device to insert said key and to simultaneously close one of said control switches to cause said shifting mechanism to be operated, and operable when shifted in the opposite direction to close the second switch, said member being held yieldingly in mid position and having a lost-motion connection with said device which permits said device to automatically withdraw said key without moving said manual member to close said second switch.

9. In a vertical hydraulic pull-down broaching machine comprising a puller head, a lifter head, a reversible-discharge pump for said puller head and hydraulic shifting mechanism for said pump, that improvement which consists in providing a continuously operating auxiliary pump for said lifter head, a pilot-operated relief valve for said pump, upper and lower normally closed control valves for said relief valve, and means on said lifter head to open one of said control valves at its upper limit of travel and the other control valve at its lower limit of travel, thereby causing said relief valve to by-pass the discharge of said pump to atmospheric storage at both ends of the lifter head travel.

10. In a vertical hydraulic pull-down broaching machine comprising a puller head, a lifter head, a reversible-discharge pump for said puller head and hydraulic shifting mechanism for said pump, that improvement which consists in providing a continuously operating auxiliary pump for said lifter head, a pilot-operated relief valve for said pump, upper and lower normally closed control valves for said relief valve, and means on said lifter head to open one of said control valves at its upper limit of travel and the other control valve at its lower limit of travel, said relief valve connecting said auxiliary pump to operate said lifter head when both control valves are closed but connecting said pump to atmospheric storage when either control valve is open.

11. In a vertical hydraulic pull-down broaching machine comprising a puller head, a reversible-discharge pump for said puller head and hydraulic shifting mechanism for said pump, that improvement which consists in providing a broach key inserting device for said puller head, electric means coordinated with said inserting device and effective to render said hydraulic shifting mechanism operative to adjust said pump to discharge in a selected direction after said key had been inserted, and direct and positively acting mechanical means effective to restore said pump to no-discharge position when the desired travel of the puller head is completed in said selected direction.

12. In a vertical hydraulic pull-down broaching machine comprising a puller head, a reversible-discharge pump for said puller head and hydraulic shifting mechanism for said pump, that improvement which consists in providing electric means to render said hydraulic shifting mechanism operative to adjust said pump to discharge in a selected direction, direct and positively acting mechanical means effective to automatically restore said pump to no-discharge position when the desired travel of the puller head is completed in either direction, and means to automatically condition said hydraulic shifting means for automatic mechanical control as soon as the operative circuit of said electric means is broken.
13. In a vertical hydraulic pull-down broaching machine, a lifter head, hydraulic actuating means therefor, a valve for said means, a separate solenoid to actuate said valve in each direction, circuits for said solenoids, a manually operated switch in one circuit, a second switch in the other circuit, and means on said lifter head effective to close said second switch as said lifter head moves upward only.
14. In a broaching machine, a broaching ram, a piston connected by a piston rod to said ram, a cylinder for said piston, a reversible-discharge pump, connections from said pump to both ends of said cylinder, a control pipe connected to the piston rod end of said cylinder, and a normally closed vent valve connected to the other end of said cylinder, said vent valve being opened by pressure in said control pipe and permitting surplus displaced oil to escape.
15. In a vertical hydraulic pull-down broaching machine comprising a fixed work support, a reciprocable puller head, a reciprocable lifter head, a reversible-discharge pump for actuating said puller head and hydraulic shifting mechanism for said pump, that improvement which consists in providing auxiliary hydraulic operating means for said lifter head, and control devices for said auxiliary means which prevent downward movement of said lifter head to insert a broach in the puller head unless said puller head is in fully raised position.
16. In a vertical hydraulic pull-down broaching machine comprising a fixed work support, a reciprocable puller head, a reversible-discharge pump for actuating said puller head and hydraulic shifting mechanism for said pump, that improvement which consists in providing a control valve for said hydraulic shifting mechanism, and a device effective to prevent movement of said control valve to cause said hydraulic mechanism to be actuated to shift said pump for a return stroke so long as a piece of work remains in broaching position on the fixed work support.
17. In a vertical hydraulic pull-down broaching machine comprising a fixed work support, a reciprocable puller head, a reversible-discharge pump for actuating said puller head and hydraulic shifting mechanism for said pump, that improvement which consists in providing a control valve for said hydraulic shifting mechanism, and a photoelectric relay effective to prevent movement of said control valve to cause said hydraulic mechanism to be actuated to shift said pump for a return stroke so long as a piece of work remains in broaching position on the fixed work support.
